UNITED STATES PATENT OFFICE

JOSEPH SODERBERG, OF IRON MOUNTAIN, MICHIGAN

ADVERTISING SIGN

Application filed April 5, 1927. Serial No. 181,217.

This invention relates to improvements in signs and more particularly to outdoor signs which are of comparatively large size and are displayed beside roadways or on the roofs of buildings.

It is a well known fact that in advertising through the medium of display signs, the factor of motion is a very desirable one inasmuch as a sign possessing this factor will attract the 10 attention more quickly than a sign which is devoid thereof. Therefore the present invention has as one of its objects to provide a sign which will include a display surface and means for practically continuously imparting motion thereto.

More specifically it is one of the objects of the invention to provide a sign which may be readily operated through the medium of a wind mill, so that there is no expense involved 20 in maintaining the operation of the sign except that due to repair of worn parts.

The sign embodying the present invention is adapted for the display of all varieties of advertising matter or in other words is adapted 25 for use in advertising merchandise, or the business of the company, firm, or other user of the sign and in signs of this general class it is desired to present a display of the merchandise or other subject matter of the advertisement together with such wording as may be appropriate, but in such signs as ordinarily 30 constructed the wording of the sign is usually merely painted upon the display surface of the sign and is not particularly attractive. Therefore it is another object of the present 35 invention to provide for the display of the wording of a sign of this class with a simulation of constant change in the appearance of the letters constituting the same, the change, 40 in the present instance being not only in color, but also attended by the appearance of motion.

In the accompanying drawings:

Fig. 1 is a view in front elevation of a sign 45 constructed in accordance with the present invention, a portion of the front of the sign being broken away to better illustrate the upper portion of the display band of the sign;

Fig. 2 is a vertical front to rear sectional 50 view through the sign taken substantially on

the line 2—2 of Fig. 1 looking in the direction indicated by the arrows;

Fig. 3 is a vertical sectional view on an enlarged scale taken substantially on the line 3—3 of Fig. 2 looking in the direction indicated by the arrows;

Fig. 4 is a view partly in plan and partly in section illustrating the bearing for the upper end of one of the rollers about which the display band of the sign is arranged to travel.

The sign embodying the invention includes a casing which is preferably of hollow rectangular form and which may be built up of wood or sheet metal and includes a front wall 1, a rear wall 2, and end walls 3, rectangular

angle iron frames 4 and 5 being arranged within the top and bottom of the casing for connecting and relatively spacing the said walls. The casing may be made of any desired dimensions, but it will be in any event 70

of considerably greater length than depth from front to rear, this latter dimension being only sufficient to accommodate the display band which passes about rolls mounted in the ends of the casing. One of these rolls, indicated by the numeral 6, is an idle roll and is

mounted at that end of the casing which is at the right hand end of the front 1, the casing being provided in its said front 1 with a display opening 7 which is of rectangular form 80

and of considerable area or dimensions as compared to the area of the said front 1 of the casing, this front constituting, in combination with the sign or display band, the display surface of the sign. The display band

heretofore referred to is displayed through the opening 7 in a manner which will presently be more specifically pointed out. The other one of the rolls referred to is indicated by the numeral 8 and the said roll is provided at its 85 lower end with a trunnion 9 journaled in a

suitable bearing 10 at the bottom of the casing at the left hand end thereof, the said roll being provided at its upper end with a trun-

nion 11 which is journaled in a manner which 95 will now be described. Front braces 12 are arranged in the top of the casing and extend between the front and rear walls thereof and are secured at their ends to the front and rear members of the frame 4, and bolted or

100

otherwise secured as at 13 to the upper side of one of the cross members is a yoke 14 preferably formed from a sheet metal plate having its end portions struck downwardly and thence outwardly to provide attaching portions and an intermediate portion spaced above the cross member 12 upon which the yoke is secured. A bearing member 15 is provided and comprises a plate bent to provide an intermediate bearing portion 16 which is formed between its ends with an opening (not shown) to accommodate the trunnion 11, the trunnion at its portion which extends above the bearing portion 16 being square as shown in Figure 3 of the drawings for a purpose to be presently explained. The plate comprising the bearing member 15 is likewise formed to provide upwardly and outwardly inclined side portions 17 which terminate in horizontally outwardly extending portions one indicated by the numeral 18 and the other by the numeral 19. The portion 18 is fitted into the space between the intermediate portion of the yoke 14 and the upper side of the cross piece 12, and a bolt 20 is removably secured through the attaching portion 19 and through the cross piece 12 upon which this attaching portion of the bearing member rests as clearly shown in Figures 3 and 4 of the drawings.

The roll 8 is adapted to be driven through the medium of a wind mill which comprises a suitable frame structure 21 mounted upon the top of the casing at the left hand end thereof, bracket members 22 being preferably provided for this purpose and secured to the front and rear sides of the upper frame 4 of the casing, and these bracket members are preferably provided with openings 23 for the connection of guy cables (not shown) leading to suitable anchors driven into the ground in juxtaposition to the sign. The wind mill shaft is indicated by the numeral 24 and the said shaft is mounted at its upper end in a suitable bearing 25 provided at the top of the frame structure 21. The lower end of the shaft 24 is squared as indicated by the numeral 26 and a bearing 27 is mounted upon the top of the casing, preferably upon the intermediate portions of the bracket members 22, and has an opening 28 formed therein to accommodate the portion of the shaft 24 above its squared lower end portion 26. A collar 29 is formed integrally upon the shaft 24 or it may be formed separately and secured in any suitable manner and the upper side of the bearing 27 and the under side of the collar are formed with opposing ball races as shown in Figure 3, bearing balls 30 being arranged within the races. In this manner the shaft 24 is supported in vertical alinement with the axis of the roll 8 and the lower end of the shaft is adapted to be connected with the upper end of the trunnion 11 of the roll 8 so as to impart rotary motion to the roll in

the rotation of the shaft, the means employed for connecting the squared lower end of the shaft and the squared upper end of the trunnion being in the nature of a box-like or rectangular sleeve 31 which is slidably engaged or fitted upon these parts. It will be observed at this point, by reference to Figure 3, that when the sleeve is resting by gravity in the position shown in the said figure with its lower end seating upon the bearing member 16, the sleeve will enclose both the lower end of the shaft 24 and the upper end of the trunnion 11 and inasmuch as the sleeve is of rectangular form and snugly fits the shaft end and the trunnion, the trunnion will be connected for rotation with the shaft. It will be evident, however, that when it is desired to remove the roll 8 for the purpose of changing the display band, as will presently be more specifically described, the sleeve 31 may be slid upwardly upon the squared lower portion 26 of the shaft 24 until its lower end has cleared the upper end of the trunnion 11 whereupon the bolt 20 may be removed and the bearing member 15 swung or sprung upwardly until its bearing portion 16 clears the upper end of the trunnion thus permitting the roll to be tilted and its lower trunnion 9 unstepped from the bearing 10. A bevel gear 32 is fixed upon the upper end of the windmill shaft 24, and this gear meshes with a similar gear 33 fixed upon a shaft 34 rotatably journaled in the head 35 of the windmill and carrying the wind wheel comprising the usual assemblage of blades 36, the vane of the windmill being indicated by the numeral 37 and being mounted at the side of the head 35 opposite the side at which the wind wheel 36 is located.

The display band of the sign is indicated by the numeral 38 and the said band is endless and may be made of canvas or any other flexible material found suitable for the purpose, the band being of a width equal substantially to the length of the rolls 6 and 8 and being trained about the rolls as clearly shown in the drawings. Upon the band there will be painted or otherwise represented, as at 39, pictorial illustrations or advertising matter of any desired character but preferably of the character stated. It will be observed that the illustrations 39 occupy that portion of the area of the display band 38 which is presented to view through the opening 7 in the travel of the band. In connection with such advertising matter it is usually desirable to display a slogan or some text matter relative to the commodity or business advertised and therefore the wall 1 of the casing may have formed in it a number of stenciled characters constituting the letters of one or more words, as indicated by the numeral 40. The mere display of slogans or words possesses a certain value from an advertising point of view, but where such dis-

play is accompanied by some other factor such as motion or change in appearance, the attractiveness of the display is greatly enhanced and for this reason the sign band 38 has painted or otherwise represented upon its surface at its upper edge portion a continuous series of diagonally arranged stripes or color strip areas 41 which are of different colors and it will be evident by reference to Figure 1 of the drawings that as the sign band travels past the opening 7 and past the stencil openings 40, the advertising matter 39 will be displayed through the former opening, and the stencils 40 will appear to be constantly changing in color and with the effect of motion due to the passage of the stripes or color strip areas 41 past the said stencils, and therefore attention will be attracted to this portion of the display as well as to the pictorial advertising matter 39.

It is to be understood, of course, that various changes may be made, within the scope of what is claimed, without departing from the spirit of the invention.

Having thus described the invention, what I claim is:

1. In outdoor display advertising apparatus, an elongated relatively shallow rectangular casing having a display opening in its front wall, spaced rotatable rolls mounted within the casing in rear of the wall, an endless display band trained about the rolls and having one of its stretches extending across the display opening, and a wind mill mounted above and supported solely by the casing and having a power shaft and driving head rotatable about the axis of the power shaft and carrying a wind wheel and wind vane, said windmill having its power shaft operatively connected with one of said rolls.

2. In outdoor display apparatus, an elongated, relatively shallow, rectangular casing having a display opening in its front wall and provided, in its said wall, above said opening, with openings defining the characters of advertising matter, an endless display band supported for travel within said casing with one of its stretches passing behind said front wall, the display band bearing pictorial advertising matter upon a longitudinal portion of its surface for display through said opening in the front wall of the casing and bearing upon another longitudinal portion, color areas positioned to pass the openings in the portion of said front wall above said opening through which the last mentioned matter is displayed, the said color areas being diagonally arranged upon said portion of the band.

In testimony whereof I affix my signature.
JOSEPH SODERBERG.
